ULTRA HIGH FREQUENCY ROTATABLE JOINT

George L. Ragan, Cambridge, Mass., assignor, by
mesne assignments, to the United States of
America as represented by the Secretary of War

Application April 18, 1944, Serial No. 531,607

8 Claims. (Cl. 178—44)

1

This invention relates to a joint for high frequency conductors, and particularly to a rotatable joint comprising a coupling between a rectangular wave guide and a coaxial line disposed at right angles to the guide.

The principal object of the invention is to provide a right angle rotatable joint of this character wherein the conductor for transmitting wave energy will be changed from rectangular to coaxial without substantial losses due to reflections. Another object contemplates a rotatable joint wherein a substantially good low resistance path for high frequency currents is provided without the use of relatively moving contacts. The joint also is substantially free from losses due to radiations. A further object is to provide a joint where one or more concentric coaxial cables may be rotatably associated with a stationary wave guide, the respective coaxial cables being adapted to rotate at different speeds. This feature is useful in instances where more than one line is required for a rotating device such as an antenna.

In the drawing, Fig. 1 is a sectional view on a diametral plane through a rotatable joint, and Fig. 2 is a sectional view on the line 2—2 of Fig. 1 which is partly broken away for clarity.

Referring to Fig. 1, a rectangular wave guide 5 has opposite *b* (wide) sides 6 and 7 and *a* (narrow) sides 8, constructed in the usual manner and with predetermined ratio between *b* and *a* sides. A circular opening is provided in wide side 6, and a coaxial cable housing 10, extending at right angles to said wide side 6 of the guide, is rigidly secured to said side in aligned relation with said opening. The diameter of the circular opening may be of the order of half the width of side 6, this dimension being generally determined by a bunching of the electric field in a manner hereinafter described. Housing 10 is preferably cylindrical in shape, the end thereof affixed to the guide being reduced in section to provide interior annular shoulder 11.

A coaxial cable, indicated generally by 15, having a tubular central conductor 16 and spaced outer conductor 17, is mounted for rotation within housing 10. Central conductor 16 is maintained within outer conductor 17 in any usual manner, as for example by means of insulating spacer beads 18, or, if desired, conductor 16 may be free to rotate with respect to conductor 17. A metallic sleeve 19 snugly encircles outer conductor 17 for a substantial length within the housing 10 and is secured thereto in any suitable manner as by solder. A cylindrical bearing spacer 20 is rigidly associated with sleeve 19, means such as set screws

21 being provided to fix the two together. A bearing sleeve 22 lies against the interior of the housing 10, in opposed relation to bearing spacer 20, and a plurality of roller bearings 23 and 24 carried in annular retainers 25 and 26 are disposed between bearing spacer 20 and opposing sleeve 22. Ring 27 serves to space bearing supports 25 and 26 properly with respect to each other. Thus coaxial cable 15 is rotatably associated with housing 10.

Referring to the lower end of housing 10, an annular gasket 30 having ring seal 31 is disposed between opposing gasket retainers 32 and 33, the latter lying against housing shoulder 11. Retainer 32 bears against the lower ends of spacer 20, sleeve 22 and annular bearing retainer 25. Gasket 30, which may be of the usual neoprene (rubber) type, extends between the sleeve 19 and housing 10 to seal the rotatable electric joint from the mechanical bearing assembly, thus to prevent dirt and oil from entering to cause possible arcing.

In the upper end of housing 10, a gasket retainer 40 spaces the bearing assembly from annular gaskets 41 and 42. These gaskets, which have ring seals 43 and 44, respectively, extends between conductor sleeve 19 and housing 10 to seal the joint in a pressure-proof manner. Gaskets 41 and 42 likewise may be made of neoprene. Upper gasket retainer 46 loosely encircles sleeve 19 and provides a bearing surface for inwardly extending flange 47 of assembly nut 48. Nut 48 may be detachably associated with the end of housing 10 by a threaded connection, as shown in the drawing.

Central conductor 16 of coaxial cable 15 extends through the space within guide 5. Conductor 16, if desired, may also constitute the outer conductor of a concentric coaxial cable having an inner conductor 49. This latter conductor may be suitably mounted for rotation relative to conductor 16. If such a secondary coaxial line is provided, conductor 16 may project beyond guide side 7, a circular opening being provided in the side to pass the conductor, as shown in the drawing.

A metallic plate 50 is rigidly secured to the inner surface of guide side 7 around the above-mentioned opening, a depending annular flange 51 thereof being snugly received in said opening. Flange 51 defines a central opening within which is mounted an annular bearing 52 journaled about the opposed end of conductor 16. An annular flange 53 may be provided on conductor 16 to cooperate with bearing 52 in order to position the conductor axially within the joint. Thus con-

ductor 16 is adapted to rotate freely in bearing 52. An annular fitting 54 is disposed about and spaced from conductor 16 within wave guide 5, the fitting being tapered from a narrow diameter at the top adjacent the circular opening in side 6 to a diameter at the bottom corresponding substantially to the diameter of plate 50 with which it is associated. Fitting 54 cooperates with the electrical joint in a manner presently to be described. A cap 55 surrounds conductor 16 and encloses the opening in side 7. Cap 55 is secured to the side 7 by bolts 56 and 57 extending through the cap, guide side 7, plate 50 and threaded into fitting 54. Rubber gaskets 58 and 58a may be used in conjunction with cap 55, if the system is to be kept under pressure.

Wave guide 5 has its end beyond the joint structure closed by a seal 59 and rounded in accordance with the shape of associated plate 50 and fitting 54, best shown in Fig. 2.

Metallic fitting 54, disposed in the wave guide 5 in aligned relation with coaxial cable 15, tends to concentrate the electric field. For this reason the coaxial cable is somewhat smaller than the width of associated guide side 6.

In order to provide a low impedance at the junction of the two conductors, fitting 54 has an interior annular channel 60 constituting part of a resonant cavity. The depth of channel 60 from its end 61 adjacent bearing 52 to its inner end 62 is generally a quarter wave length of the transmitted frequency. Channel 60 communicates with annular free space 63 defined by conductor 16 and spaced fitting 54, the depth of space 63 from common end 61 to its opposite end 64 being likewise a quarter wave length. Thus channel 60 and space 63 together comprise a half wave resonant cavity terminating at end 64. Such a cavity provides a path of low impedance to high frequency currents between fitting 54 and rotatable central conductor 16, thus permitting a smooth flow of energy between the wave guide and the coaxial line. In this manner, substantial losses due to reflections are avoided. In addition, journalled bearing 52 is at the quarter wave point of the cavity, and thus at a substantially open circuit point in the system. Therefore, little or no current theoretically passes between the rotating conductor surfaces. In practice and because of variations in frequency, some currents may pass, and for this reason it may be desirable to run the bearing dry or with graphite rather than oil which may be carbonized by current arcs.

An annular choke structure 65 is disposed within the reduced end of housing 10. Structure 65, which comprises a stationary section of outer conductor in the coaxial cable, has an upstanding annular flange 66 spaced from the housing wall to define an annular quarter wave cavity 67. This cavity acts as a choke to prevent radiation and consequent loss in a direction normal to the coaxial cable. Flange 66 is spaced from outer conductor 17 of the rotatable coaxial cable to define a communicating cavity 68, also a quarter wave in length. Cavities 67 and 68 thus form a half wave resonant cavity which reflects a low impedance for high frequencies to the discontinuity point between conductor 17 and structure 65. Consequently there is a substantially reflection-free flow of energy between these spaced conductors. It will be noted that the interior surfaces of conductor 17 and structure 65 preferably lie in the same cylindrical plane at the spaced junction. The interior annular surface of structure 65 away from the junction is rounded, as

shown at 69, this surface corresponding generally in shape to opposing surface 70 of tapered fitting 54. These smooth opposing surfaces shape the electric field for proper orientation with respect to the two coupled conductors.

Thus the present invention provides a rotatable joint constituting a high frequency transition section between a rectangular wave guide and a coaxial line. The two conductors are coupled at right angles to each other, and regions of low impedance are provided to minimize reflections due to the generally sharp impedance discontinuity present in such a coupling. Low impedances are obtained by the use of half wave resonant cavities disposed in the joint in such a manner as to reflect low impedance to the spaced junctions of the conductors. In this manner a substantially continuous non-metallic circuit is provided in the joint. Also, the relatively rotating contact surfaces lying in the path of current flow are positioned at the quarter wave point with reference to one of the cavities, whereby current flow between such surfaces is a minimum. Further, a quarter wave choke is provided to prevent radiations and consequent losses radially of the coaxial cable. The joint also is adapted to contain more than one coaxial line if desired. Such additional lines may be concentrically mounted for rotation within the primary coaxial cable. Inasmuch as several lines may be necessary to a device such as a rotating antenna, the range of usefulness of the present invention is substantially increased.

Having thus described the invention, what I claim as new and desire to secure by Letters Patent is:

1. In a high frequency transmission system, a rotatable joint construction comprising a rectangular wave guide having a sealed end to close the same, said wave guide having a circular aperture in one wide side adjacent said sealed end, a circular conductor supported at said aperture and extending at right angles from said wave guide and forming one section of outer conductor for a coaxial line, a second section of circular conductor aligned with the first section, means for rotatably supporting said second section with respect to said first section, a central conductor for said coaxial line, said central conductor having one end extending through said wave guide aperture at least to the opposite side of said wave guide, means for rotatably supporting said end of said central conductor, and a fitting carried by said opposite side of said wave guide for providing a transition structure between said opposite side of said wave guide and the said central conductor, said fitting comprising a stationary annular structure surrounding said central conductor and spaced therefrom, said fitting extending from said opposite side of the wave guide to a termination near the aperture in said first side of said wave guide and tapering to a smaller diameter as said aperture is approached, said fitting having an internal annular channel communicating with the free space between said fitting and said central conductor, said annular channel and said free space together having an effective length of substantially a half wave length whereby a good low impedance path is provided for high frequency energy between said stationary fitting and said central rotatable conductor.

2. The combination of claim 1 wherein a tubular housing encircles and is spaced from said second section, and said first section of outer conductor comprises an annular structure dis-

posed about said circular aperture, said structure having an annular flange extending between and spaced from said second section of coaxial cable and said housing and defining a half wave resonant cavity, one quarter wave of which is on each side of said flange, thus to provide a choke to radiation in a direction normal to said line.

3. The combination of claim 1 wherein a tubular housing encircles and is spaced from said second section, and said first section of outer conductor comprises an annular structure associated with the guide side about said circular aperture, said structure having an annular flange disposed between and spaced from said housing and said second section of circular conductor, said flange, housing and second section defining therebetween a half wave resonant cavity whereby a low impedance path for high frequency energy is provided between said stationary first section and said rotatable second section.

4. The combination of claim 1 wherein said means for rotatably supporting the end of said central conductor is disposed proximate to the quarter wave point of the said annular channel and communicating free space between said fitting and said central conductor, whereby a substantially high impedance is provided at said means.

5. The combination of claim 1 wherein said central conductor extends beyond said wave guide through an aligned opening in said opposite guide side, said central conductor being tubular, and there are also a second central conductor coaxial with and of lesser diameter than said first central conductor, and means for rotatably supporting said second central conductor with respect to at least one of the other conductors.

6. A rotatable joint, comprising a stationary wave guide, including first and second wall portions on opposite sides thereof, the first of which wall portions is pierced by an opening, a first section of outer tubular conductor for a coaxial line secured to said wave guide outside of and substantially coaxial with said opening, the axis of said first section of outer conductor being substantially normal to the axis of said wave guide, a smooth annular first transition surface intermediate said first wall and said first section of outer conductor, a second section of outer tubular conductor for a coaxial line having an inside dimension similar to said first section and disposed coaxially with said first section, the adjacent ends of said first and second sections of outer conductor being spaced from each other so as to form a first gap therebetween, means to sustain said second section of outer conductor to allow it to rotate about its axis, an inner conductor for a coaxial line extending through said first and second sections of outer conductor and coaxial therewith, means to sustain said inner conductor to allow it to rotate about its axis, a fitting secured to said second wall coaxial with said inner conductor and extending toward the opening in said first wall, the outer surface of

said fitting forming a substantially smooth second transition surface intermediate the second wall of said wave guide and said inner conductor, the edge of said second transition surface adjacent said inner conductor being spaced therefrom so as to form a second gap therebetween, a first half wave resonant cavity terminating at said first gap and presenting a low impedance at said first gap, and a second half wave resonant cavity terminating at said second gap and presenting a low impedance at said second gap.

5 7. A rotatable joint as defined in claim 6, wherein said first resonant cavity has a quarter wave point adjacent the means to sustain the second section of outer conductor so as to present a high impedance to curtail electrical losses, and wherein said second resonant cavity has a quarter wave point adjacent the means to sustain the inner conductor so as to present a high impedance to curtail electrical losses.

10 8. In a high frequency transmission system, a rotatable joint construction, comprising a wave guide, said wave guide having an aperture in one side, a tubular conductor supported at said aperture and extending substantially at right angles to said wave guide and forming one section of outer tubular conductor for a coaxial line, a second section of tubular conductor aligned with said first section, means for rotatably supporting said second section with respect to said first section, a central conductor for said coaxial line, said central conductor having one end extending through said wave guide aperture and toward the opposite side of said wave guide, means for rotatably supporting said central conductor, and a fitting carried by said opposite side of said wave guide for providing a transition structure between said opposite side of said wave guide and said central conductor, said fitting comprising a 15 stationary annular structure surrounding said central conductor and spaced therefrom, said fitting extending from said opposite side of the wave guide to a termination near the aperture in said first side of said wave guide and tapering to a smaller diameter as said aperture is approached, said fitting having an internal annular channel communicating with the free space between said fitting and said central conductor, said annular channel and said free space together 20 having an effective length of substantially a half wave length whereby a good low impedance path is provided for high frequency energy between said stationary fitting and said central rotatable conductor.
